COMBINED LIGHTING FIXTURE AND SUPPORT POST THEREFOR

Howard Daum, Gettysburg, Pa., assignor to Hadco Products, Inc., Littlestown, Pa., a corporation of Pennsylvania

Original design application Jan. 30, 1968, Ser. No. 10,372.
Divided and this application Dec. 20, 1968, Ser. No. 15,827

Term of patent 14 years

Int. Cl. D26—03

U.S. Cl. D48—31

FIG. 1 is a front elevational view of the combined lighting fixture and support post, said post being broken away to indicate indeterminate length.

FIG. 2 is a side elevational view thereof taken on line 2—2 of FIG. 1, the lighting fixture being fragmentarily shown for convenience of illustration.

This is a division of design application, Ser. No. D. 10,372, filed Jan. 30, 1968.

I claim:

The ornamental design for a combined lighting fixture and support post therefor, substantially as shown and described.
